ELECTRIC LAWN TRIMMER

Jerome E. Moberg, Ellicottville, N. Y., assignor, by mesne assignments, to Dunfield-Durkee, Inc., a corporation of Utah

Application March 27, 1953, Serial No. 24,221

Term of patent 14 years

(Cl. D40—1)

Fig. 1

Fig. 2

Fig. 3

To all whom it may concern:

Be it known that I, Jerome E. Moberg, a citizen of the United States, residing at Ellicottville, in the county of Cattaraugus and State of New York, have invented a new, original, and ornamental Design for an Electric Lawn Trimmer, of which the following is a specification, reference being had to the accompanying drawings, forming part thereof.

Figure 1 is a front perspective view of an electric lawn trimmer showing my new design;

Figure 2 is a bottom plan view thereof; and

Figure 3 is a rear perspective view of the same.

I claim:

The ornamental design for an electric lawn trimmer, as shown.
